UNITED STATES PATENT OFFICE.

ALANSON P. BRUSH, OF DETROIT, MICHIGAN.

CARBURETER.

1,304,449.

Specification of Letters Patent. Patented May 20, 1919.

Application filed June 27, 1917. Serial No. 177,193.

To all whom it may concern:

Be it known that I, ALANSON P. BRUSH, a citizen of the United States, residing at Detroit, in the county of Wayne and State of Michigan, have invented a certain new and useful Improvement in Carbureters, of which the following is a full, clear, and exact description.

The object of this invention is to provide a carbureter which, when connected with an internal combustion engine, will produce from liquid fuel such explosive mixtures of fuel vapor and air as are best suited for causing the engine to start easily, to idle, or to run at any desired speed.

The invention consists in the construction and combination of parts shown in the drawings, hereinafter described and pointed out definitely in the appended claims.

In the drawings, Figure 1 is a sectional side elevation of the carbureter in which the present invention is embodied. Fig. 2 is a front elevation thereof, on a smaller scale.

Referring to the parts by reference characters, 10 represents the air tube of the carbureter; and this is preferably flanged at its discharge end to facilitate its connection with the inlet manifold of the engine. The other end of the air tube, during the ordinary running conditions, is open to the atmosphere. The valve 12 in this tube, adjacent the air inlet end thereof, is merely a choke valve which may be closed to whatever extent is necessary to promote the starting of the engine.

In this air tube is a balanced suction controlled valve 15 which, when closed will substantially prevent any flow of air through the air tube. This valve as shown is a light 40 piston having a nice sliding fit in a cylinder 16, which is closed at its upper end by a tightly fitting cap plate 14, said cylinder being preferably cast integral with the air tube with its axis at right angles thereto. The piston valve is of such length that when it is down, and therefore shutting off the flow of air through the air tube, it will still project into this cylinder. A light spring 17 acts to hold the valve in the closed position, 45 but with a force such that a slight reduction of the air pressure in the cylinder 16 will cause said valve to lift. The tension of the spring may be adjusted by means of a screw 18 which screws down through the plate 14, and has on its lower end a pressure plate 19 that bears upon the top of said spring 17.

20 represents the carbureter float chamber and 21 the fuel discharge nozzle therefrom. This nozzle discharges upward through a calibrated jet opening into a fuel vaporizing tube 25. This tube 25 is extended to and is in open communication with the air tube 10 adjacent the discharge end thereof. For a part of its length this tube is so disposed that it will be sufficiently heated by the exhaust gases to cause the result hereinafter specified. As shown this tube passes vertically through the exhaust manifold 30 of the engine. The walls of the tube are of thin metal; and therefore will be heated by the 70 exhaust gases. Within this tube 25 at some suitable point between the nozzle 21 and the exhaust manifold is a restricted calibrated opening 26. In this tube 25 is also a hole 27 to the atmosphere. A valve 28 is, however, provided for closing this hole or opening it to any degree required. This valve screws down through a boss on the upper wall of the tube 25, and is provided with an operating handle 29 whereby it may be turned to 80 whatever extent is desired. This valve serves as the air throttle valve for the device.

An air tube 32 extends from the vaporizing tube 25 to the upper end of the cylinder 16 and is in open communication with both.

When the engine is idle the valve 15 will be closed by its spring and by the action of gravity. When, however, the engine is turned over for the purpose of starting it, the valve 28 should be nearly closed. Therefore, on the suction strokes of the engine, there will be produced in the tube 25 such a reduction of pressure as will cause fuel to flow from nozzle 21 and thence through the calibrated opening 26, and to be thoroughly 95 atomized and drawn into the air tube 10. At this time the valve 12 should be nearly closed so that even if the valve 15 should open a very small quantity only of air will be admitted to the device through the air tube 10 for mixture with the fuel. The result will be that, at first, a very rich mixture of fuel vapor or spray and air will be discharged into the air tube 10 and will thence flow into the engine. When the engine is 105 started, the valve 12 should be opened; and to keep the engine idling, i. e., merely running without carrying load, the air throttle valve 28 should be opened.

When the valves are in the stated positions, the volume of the explosive mixture formed will be small, and will be made up

for most part of such air as enters through the small valve controlled opening 27; and the spray and vapor of fuel drawn through the nozzle. After the engine has been running for a short time the part of tube 25 which is within the influence of the exhaust gases will get very hot; wherefore all of the mixture of air and fuel which flows through tube 25 will get highly heated;—a condition which is particularly desirable when the engine is idling, or running under a very light load.

When it is desired to produce a larger volume of less rich mixture, the air throttle valve 28 is turned toward the closed position. At each suction stroke of the engine, a reduction of pressure will be produced in tube 25, and this will increase the rate of fuel flow through the fuel nozzle. But as the pressure is reduced in the tube 25, so will it be reduced in cylinder 16; and this will cause a proportionate opening of the valve 15 thereby permitting air to flow through tube 10 to mix with the very rich mixture flowing through the tube 25.

If valve 28 be entirely closed there will be practically nothing but fuel spray and vapor which flows through the tube 25; but in that event the valve 15 will be opened widely enough to supply the necessary air to produce when mixed with said fuel, a mixture of the required proportions, and in sufficient volume to cause the engine to deliver the maximum power output.

It is easy to determine what size the calibrated opening 26 should be in order that, when valve 28 is closed, a given reduction of pressure in tube 25 adjacent the nozzle will be produced by each suction stroke of the engine to which the carbureter is to be attached. It is likewise easy to determine the necessary size of the nozzle jet opening 21 in order that a certain reduction of pressure shall cause the desired rate of fuel flow into said tube 21.

Having made these openings 26 and 21 of the proper sizes, one may control the actual reduction of pressure in tube 25 and cylinder 16, due to the suction strokes of the engine, by opening and closing the valve 28, so as, at all times, to proportionately increase or diminish the rate of flow of fuel into and of air through the air tube 10.

What actual ratio of fuel and air will be in the explosive mixture so formed will depend largely upon the responsiveness of valve 15 to changes of pressure in cylinder 16. This obviously may be regulated to produce the desired ratio by adjusting the tension of the spring 17.

Not only does the described construction provide means to control the delivering to the engine an adequate volume of explosive mixture to produce desired variations in the

power output of the engine, but it produces other results which contribute largely to the efficiency of the engine. All of the fuel and air which passes through the hot part of tube 25 is heated to a degree above that required to certainly vaporize the fuel content. When the engine is idling nearly all of the explosive mixture delivered to the engine is so heated, whereby it is expanded. This contributes to low compression in the cylinder, which is desirable when the engine is idling, and it also insures the ignition of the charge. But when the engine is delivering its maximum power output, and the throttle is positioned as stated to cause this result, only the fuel content of the produced mixture is heated, while the greater part,—the air of the mixture, is not heated. The result is a relatively cold mixture, which causes high compression in the cylinder, which is desired under the conditions stated. It is also obvious that by the manipulation of the throttle the described changes are produced gradually.

Having described my invention, I claim:

1. In a carbureter, the combination of an air tube, an automatically-closing suction controlled valve to vary the rate of air flow therethrough, a small fuel tube whose diameter is substantially less than the diameter of the air tube, and which is in open communication with the air tube between the discharge end thereof and the valve therein, a fuel jet nozzle in communication with a source of fuel supply and arranged to discharge into said fuel tube, means to prevent and regulate the admission of air into said fuel tube, and means to subject the air tube valve to substantially the same reduced pressure conditions as exist in said fuel tube adjacent the fuel jet nozzle. 100

2. In a carbureter, the combination of an air tube, an automatically-closing suction controlled valve to vary the rate of air flow therethrough, a small fuel tube which is in open communication with the air tube between the discharge end thereof and the valve therein, a fuel jet nozzle in communication with a source of fuel supply and arranged to discharge said fuel tube, means to prevent and regulate the admission of air into said fuel tube, and means to subject the air tube valve to substantially the same reduced pressure conditions as exist in said fuel tube adjacent the fuel jet nozzle, the exhaust manifold of the associated engine, the said fuel tube being extended through said exhaust manifold. 110 115

3. In a carbureter, the combination of an air tube, a suction controlled valve to vary the rate of air flow therethrough, a small fuel tube which is in open communication with the air tube between the discharge end thereof and said valve, a fuel jet nozzle con- 120 125

nected with the source of fuel supply and discharging into said fuel tube, said fuel tube being restricted to a small passageway between the fuel jet nozzle and the discharge 5 end of said fuel tube, means to control and regulate the flow of air into said fuel tube, and means to subject said air tube valve to substantially the same reduced pressure conditions as exist in said fuel tube adjacent 10 the fuel nozzle.

4. In a carbureter, the combination of an air tube, a cylinder in open communication therewith, an automatically closing piston valve movably supported in said cylinder 15 and adapted to extend across and close said air tube, a fuel tube connected with said air tube between the discharge end thereof and said valve, a fuel jet nozzle in communication with a source of fuel supply which dis- 20 charges into said fuel tube, a pipe connecting said fuel tube with said cylinder, there

being in said fuel tube a valve-controlled air opening for the admission of air into the same.

5. In a carbureter, the combination of an air tube, a cylinder in open communication therewith, a piston valve movably supported in said cylinder and adapted to extend across and close said air tube, a fuel tube connected with said air tube between the 25 discharge end thereof and said valve, a fuel jet nozzle in communication with a source of fuel supply which discharges into said fuel tube, a pipe connecting said fuel tube with said cylinder there being in said fuel tube a 30 valve-controlled air opening for controlling the admission of air into the same, a spring acting on said valve to close it and means to adjust the tension of said spring.

In testimony whereof, I hereto affix my 35 signature.

ALANSON P. BRUSH.
